WINDOW REGULATOR

Carl Sattler and Howard B. Haskins, Toledo,
Ohio, assignors, by mesne assignments, to The
Dura Company, Toledo, Ohio, a corporation of
Ohio

Application July 5, 1927. Serial No. 203,363

4 Claims. (Cl. 268—126)

The invention relates to window regulators and has for one of its objects the provision of means for raising and lowering inner and outer windows so constructed that the means for raising and lowering the outer window may be made inoperative from outside the vehicle to permit raising the outer window so that the outer side of the inner window may be washed. Another object is to provide an improved guide 10 for normally maintaining the rack of the window regulator in engagement with its driving pinion. With these as well as other objects in view, the invention further resides in the novel features of construction and combinations and 15 arrangements of parts as are more fully herein-after set forth.

In the drawing:—

Figure 1 is an interior side elevation, partly broken away, of a portion of a vehicle to which 20 our invention is applied;

Figures 2, 3 and 4 are cross sections on the lines 2—2, 3—3 and 4—4, respectively, of Figure 1;

Figure 5 is a cross section on the line 5—5 of 25 Figure 2.

Our invention is designed particularly for use in railway cars and as shown is applied to a Pullman car, the side walls of which have pairs of adjacent window openings 1 with the chambers 2 between the pairs. These chambers are 30 formed by the uprights 3 at the edges of the openings and the inner and outer panels 4 and 5, respectively. The inner and outer panels also form with the uprights chambers 6 to one side 35 of the openings, which are adapted to receive the inner and outer windows 7 and 8, respectively, when raised.

Separate window regulators are provided for 40 operating the windows 7 and 8, each of these regulators comprising the lifter arm 9, the rack 10, the pinion 11 for driving the rack, the handle 12 and suitable irreversible drive mechanism 13 between the handle and the pinion. The lifter arm 9 extends within both chambers 2 and 6 45 and is pivotally connected intermediate its ends to the bracket 14, which is mounted upon an upright 3. The free end of the lifter arm is connected in the usual manner to the window while its other end is pivotally connected to the upper end of the rack 10, which extends 50 within the chamber 2. The pinion 11 is also mounted within this latter chamber.

To provide for washing the outer side of the inner window without the necessity of operating 55 the window regulator for the outer window, we

have provided means operable from outside the car for making the window regulator for the outer window inoperative to thereby release the outer window so that the workman may raise the same and have access to the outer side of the inner window. In detail, the pinion 11 is fixedly mounted upon the shaft 15 and in the present instance the two are integral. This shaft extends within the chamber 2 and has secured to its outer end the push button 16 which extends 60 through an opening in the outer panel 5. The shaft 15 is slidably mounted in the bearing 17 which is secured to the partition 18 extending vertically within the chamber 2 between its side walls. For driving the pinion from the irreversible drive mechanism 13, we have provided 65 the bifurcated driving member 19 and the cooperating bifurcated driven member 20, both being preferably formed of sheet metal. The driving member 19 is fixedly secured to the driven member 21 of the irreversible drive mechanism, while the driven member 20 is fixedly secured to the inner end of the shaft 15. To maintain 70 the alignment of these members, the driven member 21 of the irreversible drive mechanism has the pin 22, the outer end of which is engageable 75 in the axial bore 23 in the inner end portion of the shaft 15. There is also the sleeve 24 which is fixed upon the inner end portion of the shaft 15 and has a bearing in the partition 25 within the chamber 2 and extending parallel to the partition 18. For normally maintaining 80 the pinion 11 in engagement with the rack 10, we have provided the coil spring 26, which is located between the bases of the driving and driven members 19 and 20 and yieldably holds 85 the shaft 15 and consequently the pinion 11 in its outermost position, which is determined by the bearing 17 engaging the outer side of the pinion. The driving and driven members 19 and 20 are arranged to permit longitudinal movement 90 of the shaft 15 and associated parts a sufficient distance to disengage the pinion 11 from the rack 10, this being accomplished by the workman 95 pressing upon the push button 16. While this pinion is held out of engagement with the rack the outer window may be raised to permit washing 100 of the outer side of the inner window.

For the purpose of guiding the racks 10 so that 105 they will be held in mesh with the driving pinions, regardless of the angularity which the racks assume while operating the windows, we have provided a guide for each rack, which comprises the frame 27 having its inner end pivoted concentric with the driving pinion and having mounted at 110

its outer end the pair of spaced rolls 28, which engage the plain edge of the rack. These rolls, as shown, are mounted upon the rivets 29 secured to and extending transversely of the outer end of each frame and suitable washers 30 are also secured upon these rivets to extend at the side of the rack opposite that adjacent the frame. In the window regulator for operating the outer window, the frame 27 is journaled upon the bearing 17, as shown particularly in Figure 2, while in the window regulator for operating the inner window, the frame 27 is journaled upon the sleeve 31 which surrounds the outer end portion of the shaft 32, the driving pinion for the rack occupying the inner end portion of this shaft. This shaft is directly secured to the driven member of the irreversible drive mechanism and is also journaled in the partition 18.

From the above description, it will be seen that we have provided a window regulator construction which permits a workman outside the car making inoperative the window regulator for operating the outer window so that he may raise this outer window to have access to the outer side of the inner window. It will also be seen that we have provided an improved means for guiding the racks of the window regulators and that the guide for the window regulator operating the outer window is pivotally mounted upon a bearing for the driving pinion shaft, which is operable to disengage the driving pinion from the rack.

What we claim as our invention is:

1. The combination with a vehicle having a window opening and a window for the opening, of a window regulator for operating the window, said window regulator including a handle at the inside of the vehicle, a pinion operatively connected to said handle, a rack, a spring for normally holding said pinion in engagement with said rack, and a member operable from outside the vehicle for axially moving said pinion against

the effort exerted by said spring to disengage said pinion from said rack.

2. The combination with a vehicle having a window opening and a window for the opening, of a window regulator for operating the window, including a handle at the inside of the vehicle, a pinion operatively connected to said handle, a longitudinally movable shaft carrying said pinion and operable for longitudinal movement from outside the vehicle, a rack, a guide for the rack pivoted concentric with said shaft, and means for yieldably holding said pinion in engagement with said rack.

3. The combination with a vehicle having a window opening and a window for the opening, of a window regulator for operating the window having a handle at the inside of the vehicle, a rack, a pinion, yieldable means for normally holding said pinion in engagement with said rack, an irreversible drive connection between said pinion and handle, and means operable from outside the vehicle for moving said pinion against the action of said spring to disengage the same from said rack.

4. The combination with a railway car having a window opening and a chamber at one side of the opening, and a window for the opening, of a window regulator for operating the window extending within the chamber, said regulator including a shaft, bearings within the chamber for said shaft, a pinion carried by said shaft, a rack, a guide for said rack pivoted upon one of said bearings, a coil spring for normally holding said pinion in engagement with said rack, a handle at the inside of the car, an irreversible drive mechanism between said handle and pinion, and means upon said shaft operable from outside the car for longitudinally moving the same to disengage said pinion from said rack.

CARL SATTLER.

HOWARD B. HASKINS.
